PNEUMATIC MOUNTING FOR EXCAVATING MACHINES

Norman De Wind, Newton, Iowa, assignor to The Parsons Co., Newton, Iowa, a corporation

Application July 29, 1932, Serial No. 625,787

3 Claims. (Cl. 37—86)

The object of my invention is to provide a pneumatic mounting of very simple construction so arranged as to reduce the transmission of the strain and shock of digging operations from the 5 digging apparatus to the main frame of the machine to a minimum.

With this and other objects in view, my invention consists in the construction, arrangement and combination of the various parts of my pneumatic mounting for excavating machines, whereby the objects contemplated are attained, as hereinafter more fully set forth, pointed out in 10 my claims, and illustrated in the accompanying drawing, in which:

15 Figure 1 is a side elevation of a portion of an excavating machine equipped with a pneumatic mounting embodying my invention.

Figure 2 is a detailed, sectional view taken on the line 2—2 of Figure 1.

20 Figure 3 is a vertical, detailed sectional view taken on the line 3—3 of Figure 2; and

Figure 4 is a side elevation of a slightly different form of my improved mounting.

25 My invention is particularly designed for use with excavating mechanisms of the kind which have a boom pivoted to the main frame of the machine near one end of such frame.

30 On the boom is mounted an endless chain and a bucket type of excavating mechanism. The excavating mechanism is usually operated from a power plant mounted on the main frame of the machine. The machine is mounted on wheels or other traction devices for transportation from place to place and ordinarily it travels under its 35 own power.

When the boom is lowered for digging a ditch, the machine travels just ahead of the excavating mechanism.

40 The operation of the excavating mechanism in digging the dirt from the ditch imposes great strain upon the main frame and other parts of the machine. The engagement of the buckets with the hard wall of the ditch transmits severe vibration and jerking to the main frame. Many 45 different kinds of construction have been adopted in an attempt to reduce the transmission of this vibration and strain to a minimum, but nothing heretofore has been successful.

50 The result of the transmission of the vibration from the excavating mechanism is great wear and rapid deterioration of the mechanism and particularly of the traction mechanism including axles and such parts.

55 There is a tendency to cause great up and down vibration and jerking, particularly substantially

in the vertical line extending downwardly from the axis of the shaft on which the boom is mounted. This imposes great shocks on the traction mechanism.

It is my object to provide a pneumatic device 60 arranged substantially in this line, whereby the transmission of shocks to the traction members may be very greatly reduced and the jar on the main frame and traction mechanism may be kept down as much as possible. 65

In the accompanying drawing, I have used the reference numeral 10 to indicate the main frame of an excavating machine of the type under consideration. This frame is supported as shown in Figures 1, 2 and 3 upon traction wheels 11 located 70 at the rear end and carried upon the axle 12. The mount of the axle will be later referred to in greater detail.

The frame carries an excavating mechanism including a boom 13 pivoted at its upper end on a 75 shaft 14 carried by the main frame 10. Supported on the boom is a digging mechanism of the kind having the endless chain 15 carrying the buckets or diggers 16. This digging mechanism is operated from any suitable source of power. 80

The boom 13 may be raised or lowered. When it is lowered, it inclines downwardly and rearwardly from the main machine and the forward stretch of the chain 15 brings the bucket 16 into contact with the ground and as the excavating mechanism is operated, the buckets cut and carry upwardly the dirt. 85

As each bucket strikes the ground, it engages it and causes the transmission of a strong jerk to the main frame. 90

In mechanism of this kind in which the endless chain and bucket excavating apparatus is projected downwardly and rearwardly from the main frame, there is likely to be an engagement of the buckets with stones or hard clay or the like, so 95 that the jerking and vibration transmitted to the main frame is very great. It, of course, follows, that the vibrations and jerkings submitted to the traction mechanism are great and tend to cause wear on the axles and other parts. 100

I preferably locate the shaft 14 forwardly with relation to the axle 12 so that the axle 12 is arranged between the lengthwise axis of the boom and a vertical line between the axis of the shaft 14 and the ground on which the whole machine 105 rests.

The cushioning mechanism is then located rearwardly of this vertical line.

In Figures 1, 2 and 3, I have shown the axle 12 received in housings or the like 17. These 110

are pivoted or journaled as at 18 in boxings 19. The pivot lines are lengthwise of the machine to permit the wheels to travel over obstructions and to allow for some variation in the relative 5 heights.

The boxings 19 are slidable in the vertical frames 20 for up and down adjustment. Above each of the frames 20 is mounted a downwardly opening cylinder 21. In each cylinder 21 travels 10 a piston 22 connected by a rod 23 with one of the boxings 19.

Connected with the upper end of each cylinder 21 is a valve structure 24, such as that employed in ordinary inner tubes. Air under pressure may 15 be forced into the upper ends of the cylinders 21 with the equipment at ordinary filling stations.

The wheels 11 may be provided with pneumatic tires or may be of any kind.

In the operation of a machine of the kind here- 20 tofore described, the vibrations of the digging mechanism are transmitted to the main frame and thence to the ground. The vibrations, of course, are cushioned by the pneumatic cylinders 21 and pistons 22 so that the complete force of 25 such vibrations is not transmitted through the main frame to the ground but is greatly reduced and cushioned. The cushioning operation is in line between the vertical plane of the shaft 14 and the longitudinal axis of the boom 13.

30 I find that where a pneumatic cushioning device of this kind is used the saving in wear and breakage over that experienced where no pneumatic device is used is very noticeable.

In Figure 4, I have shown an arrangement similar to that of Figures 1 to 3 inclusive except that the rear axle, which is indicated at 25, is mounted directly on the main frame without any interposed pneumatic cushion device.

It is provided with wheels 26 having large 40 pneumatic tires 27. The other parts are similar to those described in connection with the structure shown in Figures 1 to 3.

The cushioning means, of course, in the second form of my device is interposed between the axle 45 and the ground instead of between the axle and the main frame.

I find that where the structure here under consideration is employed, the whole excavating mechanism can be transmitted much more rapidly 50 from place to place than where endless train traction devices are used, and this is another advantage of using pneumatic cushioning members of the kind under consideration. They make it possible to employ ordinary wheels without the 55 danger of excessive strain and breakage.

Changes may be made in the construction and arrangement of the parts of my improved excavating machine and it is my intention to cover by my claims, any modified forms of structure or use of mechanical equivalents, which may be reasonably included within their scope.

I claim as my invention:

1. In an excavating machine having a main frame and a boom pivoted thereto near the rear end of the main frame and having endless chain and bucket mechanism carried by the boom adapted to be inclined downwardly and rearwardly from the main frame when in digging position, a transverse axle supported on the main frame, a pneumatic-tired traction wheel on said axle, and pneumatic cushioning means for cushioning the vibrations caused by the intermittent engagement of the digging elements of the machine with the ground, the axle, cushioning means and boom pivot being substantially in a vertical plane.

2. In an excavating machine having a main frame and a boom pivoted thereto near the rear end of the main frame and having endless chain and bucket mechanism carried by the boom adapted to be inclined downwardly and rearwardly from the main frame when in digging position, an axle supported on the main frame, a traction wheel on said axle, and pneumatic cushioning means for cushioning the vibrations caused by the intermittent engagement of the digging elements of the machine with the ground arranged substantially in but slightly rearwardly of the vertical plane through the pivotal connection of the boom with the main frame.

3. In an excavating machine having a main frame and a boom pivoted thereto near the rear end of the main frame and having endless chain and bucket mechanism carried by the boom adapted to be inclined downwardly and rearwardly from the main frame when in digging position, a transverse axle supported on the main frame adapted for use with, pneumatic-tired traction wheels, and pneumatic cushioning means for cushioning the vibrations caused by the intermittent engagement of the digging elements of the machine with the ground, the axle and cushioning means being arranged substantially in but slightly rearwardly of the vertical plane through the pivotal connection of the boom with the main frame arranged substantially below the pivotal connection of the boom with the main frame.

NORMAN DE WIND.
